CIGARETTE MOUTHPIECE OR THE LIKE

Glenn Davidson, Bloomington, Ill.

Application February 27, 1932, Serial No. 595,509

15 Claims. (Cl. 131—52)

This invention relates to smokers' mouthpieces, especially cigarette mouthpieces of the type comprising a plug or insert within that end of the cigarette which is received in the mouth, and to the method of and apparatus for making such mouthpieces, the present application being a continuation, in part and with respect to common subject matter, of a prior application filed February 11, 1930, Serial No. 427,511.

Such mouthpieces or inserts have been used to some extent for preventing the tobacco from coming into direct contact with the mouth, for avoiding the waste of tobacco otherwise contained in the end of the cigarette which is thrown away, and, more particularly, and when composed of fire resistant material, for the purpose of preventing the smoldering of the discarded end and consequent danger of fire. While the desirability of such devices is recognized, particularly for the purpose last referred to, they have not come into general use, partly because as heretofore devised their manufacture has involved considerable trouble and expense, adding materially to the cost of the cigarette, and partly because they have resulted in changes in the characteristics of the conventional cigarette to which the public has become accustomed.

The present invention has for one object to provide a mouthpiece or insert of this general character which can be produced in quantities and incorporated with the cigarettes during the manufacture of the latter by commercially practicable methods without adding to the cost of the cigarettes, and which will permit the cigarette to draw naturally and will, when inserted between the lips of the user, be substantially indistinguishable to the senses from the ordinary cigarette to which the smoker has become accustomed. Another object of the invention is to provide a continuous process or method by which such mouthpieces can be produced at negligible expense, and which is of such a nature as to permit a wide variation in the characteristics of the mouthpieces produced in accordance with the demands of the trade. A further object of the invention is to provide suitable mechanism by which such process or method can be readily practiced.

The foregoing and other objects of the invention will best be understood from the following description of certain embodiments thereof and the methods of and apparatus for producing the same, as illustrated in the accompanying drawings. It will be recognized, however, that the particular constructions and operations described

and shown have been chosen for purposes of exemplification merely, and that the invention, as defined by the claims hereunto appended, may be otherwise embodied and practiced without departure from the spirit and scope thereof.

In said drawings:

Fig. 1 is a perspective view, partly broken away, of a cigarette embodying the invention.

Fig. 2 is an enlarged perspective view of the mouthpiece or insert shown in Fig. 1.

Fig. 3 is a perspective view of the filler for the insert shown in Fig. 2, showing the same before being compressed and enclosed by its wrapper.

Fig. 4 is a diagrammatic side elevation, and

Fig. 5 is a diagrammatic perspective view, partly broken away, illustrating the method of and apparatus for producing the filler shown in Fig. 3 and assembling the same with its wrapper as shown in Fig. 2.

Figs. 6, 7 and 8 are views similar to Fig. 2 illustrating variations of the invention.

Figs. 9 and 10 are views corresponding to Figs. 2 and 5, respectively, illustrating another variation.

Figs. 11 and 12 are similar views illustrating a further variation.

Fig. 13 is a sectional perspective view illustrating a modification of the folding rolls shown in Fig. 5 to adapt them for use with crepe paper.

Figs. 14, 15 and 16 are views, corresponding respectively to Figs. 2, 4 and 5, illustrating a still further variation.

Fig. 17 is a perspective view showing a modified folding means.

In Fig. 1 is shown a cigarette having the usual wrapper 15 and tobacco filler 16 and also having at one end within the wrapper 15 a plug or insert 17.

In Fig. 2, the plug or insert 17 comprises a cylindrical wrapper 18, preferably of paper, enclosing a filler 19 in the form of a strip of paper or other equivalent material folded upon itself alternately in opposite directions, the folds being of progressively decreasing width from the center toward the opposite ends or rather the lateral edges of said filler and being so graduated that, when compressed to the extent shown, the perimeter of the filler will assume the cylindrical form of the wrapper, each fold constituting a substantially complete chord of the cross section of the plug and engaging said wrapper at both lateral edges.

In Fig. 6 is shown a filler 190 which is substantially like the filler 19 above described with the exception that certain of the folds are somewhat

55

narrower than the width required to constitute a complete chord of the circle in order to provide distinct air passages 28, thereby permitting a greater number of folds and a more firm and compact insert. If desired the air passages 28 may be defined by tubular extensions 280 formed on the adjacent folds of the filler 195, as shown in Fig. 7, by making said adjacent folds of a sufficiently excess length.

10 In Fig. 8 is shown filler 191, which is similar to filler 19 in Fig. 2 except that the folds are rounded instead of being sharply creased. Such an insert can be made as firm and compact as those shown in Figs. 6 and 7, the rounded folds 15 providing a multiplicity of small longitudinal air passages as well as adding distinctly to the resiliency of the insert.

The filler 19 in Fig. 2, 190 in Fig. 6, 191 in Fig. 8, and 195 in Fig. 7 can, in accordance with the present invention, be easily and cheaply produced by a simple, continuous process from a web of material of indefinite length without any rolling or analogous operations on the individual fillers. Thus, as shown in Fig. 4, a web of paper 20 drawn from a roll 11 or other source of supply, and which may, if desired, be slightly dampened, may be passed longitudinally between properly corrugated rollers 21, which may have axial recesses or passages 22 for the reception of suitable heating elements or for the circulation of a suitable heating medium. In the case of filler 19 in Fig. 2, the cooperating corrugations of the rollers 21 are so formed and proportioned as to produce longitudinal folds of widths so graduated transversely of the web 20, that when said web is subsequently cut transversely to form the individual fillers, as hereinafter explained, the folds of said individual fillers will be of less width adjacent the ends or rather the lateral edges thereof than at the center, as above described. It is believed that the modification of the rollers 21 needed to produce the necessary folds to form filler 190 in Fig. 6, 191 in Fig. 8, and 195 in Fig. 7 will be obvious without further description or illustration. The folds of said web may be compressed into the desired form by passing the folded web, after the latter leaves the rollers 21, between converging guides 23, as shown most clearly in Fig. 5, and the wrapper 18 then placed therearound and secured by means of a suitable adhesive in substantially the same way that the paper wrappers are placed around the tobacco in forming the cigarettes themselves. If desired, the wrapper may be formed of threads or narrow strips of paper or other material woven around the filler, or the wrapper may be spirally wound around the filler and fastened with adhesive. The mechanical means for accomplishing these various methods of wrapping are well known. If desired, feed rollers 27 may be employed to assist in drawing the folded web through the guides 23 and feeding the work forwardly. The resulting cylindrical stock, generally indicated at 26, in Figs. 4 and 5, may then be cut transversely, as indicated at 10, to the desired lengths which may thereafter be incorporated with tobacco to form the cigarettes, as shown in Fig. 1, in any suitable or preferred manner.

In Figs. 9 and 10 is illustrated a variation of the general folding plan above described and shown in the preceding figures. The rollers 212 for folding the web to form the filler 192 shown in these figures are so corrugated as to form a plurality of groups of folds, said folds being of different widths, being correspondingly and symmet-

rically arranged in the several groups, and being preferably alternately sharp and rounded as indicated at 33 and 34 respectively. The guide 232 is so constructed as to bend the folded web into circular form in cross section with the sharp folds 33 directed inwardly toward the center and the rounded folds 34 disposed at the periphery. Said guide 232 is of complete tubular form and may be provided with interior guiding fins 35 to assist in the even disposition of the folds.

10 In Figs. 11 and 12 is illustrated a somewhat similar folding plan wherein the rollers 213 are so corrugated that the two lateral halves of the web are each folded substantially as in the form of the invention shown in Fig. 8, these two halves 15 being then folded upon one another about the longitudinal median line 36 of the web by the tubular guide 233 to form a filler 193 of the configuration shown. The tubular guide 233 may, if desired, also be provided with a guiding fin 37 20 similar to the fins 35 shown in Fig. 10.

In all of the embodiments and modes of practicing the invention above described, the web of material is folded longitudinally in accordance with some definite plan before being gathered and compressed laterally into cylindrical form, folding rollers being shown in each instance although it will be obvious that at least some of the plans of folding can be equally well accomplished by drawing the web through fixed guides of suitable 20 form. Such a construction is shown in Fig. 17, in which the fixed guides are indicated at 121.

If desired, the paper of which the fillers are formed may be creped, in which case it is desirable that the folding rollers be such as to avoid compressing the paper in the direction of its thickness and thereby destroying the creping. In Fig. 13 is shown a pair of rollers 210 whose corrugations 30 are cut away, as indicated at 31, to avoid compressing the paper between the lines 40 of fold and are rounded at their edges, as shown at 32, to provide rounded folds as in the form of filler illustrated in Fig. 8.

Definite folding can, however, be entirely omitted in the case of certain materials, as for example crepe paper. Such paper, while relatively stiff and substantially inelastic in one direction, that is to say, the direction in which the crinkles or rugations extend, is extremely flexible and elastic, in fact substantially plastic, in 50 the direction transverse of the rugations and may be readily shaped into the desired form without definite folding. Thus, for example, as shown in Figs. 14 to 16, a web 204 of crepe paper having its rugations disposed longitudinally may be 55 drawn from the roll 11 by the feed rolls 27 or equivalent feeding means through a tubular funnel-shaped guide 234 so as to cause the same to be gathered into more or less haphazard convolutions to form a filler 194. Such a filler can be 60 made of any desired density in accordance with the weight of paper and width of web employed. This mode of practicing the invention, while particularly applicable to crepe paper, is not to be understood as necessarily limited thereto, as there 65 are undoubtedly other materials which are capable of being successfully handled in substantially the same way.

70 Preferably the paper or other material constituting the above described fillers is so constituted or treated as to be fire resistant or self-extinguishing, and is suitably sized. In addition, the material may be treated by coating or, in the case of soft sized paper, saturating the same with an infusion made from tobacco, tobacco stems, cocoa, 75

cinnamon, menthol or other flavoring materials.

At all events, it will be understood that, by employing a suitable quality of paper or other material, and a suitable number of folds (i. e. proper width of web stock to form the filler), and folding longitudinally, that is longitudinally of the mouthpiece, the insert may be made to have substantially the same firmness and to impose substantially the same resistance to the passage of air as the tobacco which it replaces, so that it will feel to the mouth substantially like an ordinary cigarette and will draw with substantially the same freedom or afford a draft substantially no greater than that of a corresponding portion of tobacco filler which is replaced thereby.

It will be seen that the type of filler described above is such as readily lends itself to modification in these respects, since the character of the paper or other material and the number of folds can be varied within wide limits to vary the firmness of the mouthpiece or the drawing qualities thereof without any substantial change in general design. For example, by using a comparatively soft paper, the feeling of an ordinary untipped cigarette can be duplicated, while by using relatively stiff, hard-sized paper, the feeling of a gold or cork tipped cigarette can be duplicated. If desired, the filler may be formed from a relatively soft web and the wrapper from a stiffer material.

It will be seen that an essential principle of the method constituting an important feature of the invention above described resides in the provision of a continuous process for forming an indefinite length of mouthpiece stock, from which the desired lengths can be cut, which process, in its broadest aspect, consists in feeding a web of suitable material and of indefinite length longitudinally while gathering or compressing the same laterally into substantially cylindrical form, either with or without definite preliminary folding. The process lends itself to considerable variation of choice of materials and in the particular plan of folding, where such is employed, in order to provide mouthpieces of any desired characteristics.

The process is an extremely simple one and by its practice cigarettes having mouthpieces of the desired characteristics may be produced at no substantial increase in cost beyond that of the stock employed, which is more than offset by the saving in tobacco replaced.

It will be understood that the inserts or plugs may be incorporated with the cigarettes in any suitable way by substituting them at the proper points for the tobacco in the ordinary operation of manufacturing cigarettes.

Having thus described my invention, I claim:

1. A mouthpiece for cigarettes and the like, comprising a tobacco replacing filler imposing a resistance to the passage of the smoke substantially equal to that of a corresponding portion of replaced tobacco and being formed of material laid in folds longitudinally, such folds varying in width.

2. A mouthpiece for cigarettes and the like, comprising a tobacco-replacing filler mass offering substantially no less resistance to the passage of smoke than the replaced portion of tobacco filler and being formed of material folded longitudinally and compressed together to leave small channels for the passage of smoke in the longitudinal direction such folds varying in width.

3. A cigarette having at one end within the wrapper an insert affording a draft substantially

no greater than that through a corresponding portion of tobacco filler replaced thereby and comprising material folded longitudinally and compressed together to leave small channels for the passage of smoke in the longitudinal direction.

4. A cigarette having at one end within the wrapper an insert affording a draft substantially no greater than that through a corresponding portion of tobacco filler replaced thereby and comprising material folded longitudinally and held compressed together by an independent wrapper element to leave small channels for the passage of smoke in the longitudinal direction.

5. A cigarette having at one end within the wrapper an insert including a strip of material folded upon itself alternately in opposite directions, the lateral folds of the strip being of less width than those at the center.

6. A cigarette having at one end within the wrapper an insert including a strip of relatively stiff, fire-resistant material folded upon itself alternately in opposite directions, the lateral folds of the strip being of less width than those at the center.

7. A cigarette having at one end within the wrapper an insert including a strip of material folded upon itself alternately in opposite directions, the folds being of progressively decreasing width from the center toward the opposite edges

30
25
35
40

8. A cigarette having at one end within the wrapper an insert affording a draft substantially no greater than that through a corresponding portion of tobacco filler replaced thereby and comprising relatively thin crinkled paper folded longitudinally and held compressed together by an independent wrapper element to leave small channels for the passage of smoke in the longitudinal direction.

9. A cigarette having at one end within the wrapper an insert including a strip of material folded upon itself alternately in opposite directions, each of the folds constituting a complete chord of the cross-section of the insert.

10. A mouthpiece for cigarettes and the like, including a strip of material folded upon itself alternately in opposite directions and enclosed in a substantially cylindrical wrapper, both lateral edges of each of said folds engaging said wrapper.

11. A mouthpiece for cigarettes and the like, including a filler in the form of a strip of material folded upon itself alternately in opposite directions, and a substantially cylindrical wrapper enclosing said filler, the lateral folds of the strip being of less width than those at the center.

12. A mouthpiece for cigarettes and the like, including a filler in the form of a strip of relatively stiff, non-absorbent fire-resistant material folded upon itself alternately in opposite directions, and a substantially cylindrical wrapper enclosing said filler, the lateral folds of the strip being of less width than those at the center.

13. A mouthpiece for cigarettes and the like, including a filler in the form of a strip of material folded upon itself alternately in opposite directions, and a substantially cylindrical wrapper enclosing said filler, the folds being of progressively decreasing width from the center toward the opposite edges of the strip.

14. An intermediate product in the manufacture of cigarettes and the like, comprising a

mouthpiece rod having a continuous filler of material, folded longitudinally and compressed together to impose a resistance to the passage of smoke substantially equal to that of a tobacco cigarette and adapted to be cut into a relatively indefinite number of mouthpieces.

15. An intermediate product in the manufacture of cigarettes and the like, comprising a

mouthpiece rod having a continuous filler of relatively indefinite length of one piece material, folded longitudinally and compressed together to impose a resistance to the passage of smoke substantially equal to that of a tobacco cigarette and adapted to be cut into a relatively indefinite number of mouthpieces.

GLENN DAVIDSON.
